DESIGN FOR A CASING FOR A BEVERAGE
DISPENSERRalph A. Nicholson, Chicago, Ill., assignor to Raymond T. Moloney, Chicago, Ill.

Application July 1, 1946, Serial No. 131,215

Term of patent 14 years

(Cl. D2—3)

To all whom it may concern:

Be it known that I, Ralph A. Nicholson, a citizen of the United States and a resident of Chicago, Cook County, Illinois, have invented a new, original, and ornamental Design for a Casing for a Beverage Dispenser, of which the following is a specification, reference being had to the accompanying drawings, forming part thereof:

Fig. 1 is a perspective view of a casing for a beverage dispenser embodying my new design;

Fig. 2 is a rearward perspective view of the same;

Fig. 3 is a top plan view of the same.

The dominant features of the new design are shown in full lines.

I claim:

The ornamental design for a casing for a beverage dispenser, as shown and described.

RALPH A. NICHOLSON.
